UNITED STATES PATENT OFFICE.

MORTIMER NORDEN, OF NEW YORK, N. Y., ASSIGNOR TO JOSEPH NORDEN,
OF SAME PLACE.

ELECTRICAL SIGN.

SPECIFICATION forming part of Letters Patent No. 606,356, dated June 28, 1898.

Application filed April 12, 1897. Serial No. 631,780. (No model.)

To all whom it may concern:

Be it known that I, MORTIMER NORDEN, a citizen of the United States, residing in the city, county, and State of New York, have 5 invented an Improvement in Switch Mechanism for Electric Signs, of which the following is a specification.

In Letters Patent No. 568,204, granted to me September 22, 1896, a monogram is represented for an electric sign, such monogram having the electric lights disposed in such a manner that any desired letter can be indicated by illuminating the proper electric lamps, and in so doing the proper circuit 10 connections are selected, and a hand mechanism is represented for such selection.

The present invention is made with reference to an automatic mechanism by which the electric lights are selected from the monogram, so that where several monograms are provided, one for each letter, and placed in a row or otherwise to constitute a sign the letters can be illuminated so as to spell the desired words and the circuit connections can 15 be made to all the monograms simultaneously, so as to illuminate the proper letters for spelling out words in succession, and then an interval is provided between the completion of the words that are to be spelled 20 and the repetition of the illumination.

In the drawings, Figure 1 is a diagrammatic illustration of a monogram and the circuit connections to the same. Fig. 2 is an end view illustrating the circuit-closer, and 25 Fig. 3 is a side view representing the circuit-closing devices and part of the driving mechanism.

It is generally advantageous to make use of an electric motor, and the same may be 30 employed for driving the shaft B and pinion C, which gives motion to the gear D, at the proper speed to revolve the same and the shaft E, that is supported in the end frames F, and upon this shaft E there are heads G, 35 adapted to receive the ends of the letter-bars H, in each of which letter-bars there is a row of holes for the reception of the movable contact-pins 2.

The rings I are each preferably made in two 40 parts, the upper one being separable from the lower, and these are advantageously united

by hinges 3 and a movable pin 4 at the slip-joints, so that the upper segments of the rings and the bars K, that are carried by them, can be swung back or lifted off to give 55 access to the cylinder formed of the end frames F and letter-bars H, in order that the letter-bars may be changed; the same being removable from the heads in any suitable manner, and it is preferable to support the 60 ends of the letter-bars on circular projecting ribs on the heads and to employ the screws 5 for connecting the letter-bars at their ends to the heads.

Upon the bars K electric contacts are provided, preferably in the form of springs 6 and 7, attached at their ends to the bars and normally separated; but when the contact-pins 2 come in contact with the springs 7 they are brought against the springs 6 to 65 close the electric circuit, and upon each bar K there are pairs of contact-springs 6 and 7, equal in number to the number of lights in one monogram, and I have represented a monogram at M similar to the monogram represented in the aforesaid patent, and hence such monogram does not require further description herein; but I do not limit myself to the specific arrangement of lamps so represented, as the present invention is available 75 with electric signs of any desired character.

I provide as many bars K as there are monograms M, such bars being advantageously placed at equal distances around the cylinder of letter-bars; and where all the monogram-signs are to be illuminated simultaneously 80 the letter-bars H should be placed in corresponding positions, so that their contact-pins 2 engage all the springs on the monogram-bars simultaneously, and it is now to be understood that the letter-bars H are to be prepared by placing the contact-pins 2 in the correct positions for closing the circuits to the proper lamps in the monograms, so as to 85 show the desired letter by the illumination 90 of the lamps.

It is to be understood that with the monogram as illustrated any letter can be displayed by the selection of the proper lamps. I have represented six of the bars K in Fig. 95 2, and with these there are to be six of the monogram-boards, (illustrated in Fig. 1,) one

to each bar. As the cylinder G is revolved six of the bars II act, in connection with the six bars K, to illuminate six letters, or if a less number of letters is required for a given word one or more bars II may be left out. When the next set of bars II comes around, the lamps are illuminated on the monogram-boards to spell the next word desired, and so on, and as there are thirty-six of the bars II the machine represented is capable of showing six words one after the other.

A convenient arrangement of circuit connections is represented in Fig. 1, in which N represents a main battery or other source of electric energy, from which a wire 8 leads to all the springs 6, and a wire 9 from each spring 7 leads to an electric lamp, and a common return-wire 10 leads to the battery. If these wires only were made use of, the electric sign might be illuminated so as to indicate the desired words by repeating the circuit-contacts for illuminating the proper letters; but as it is generally desirable to obtain a pause between one set of illuminations and another I provide upon one of the heads G a segment-bar O and a contact-brush connected to the wire 8 and a brush and wire leading from the segment-bar O to the springs 6, so that when the segment-bar O by its rotation with the cylinder-heads G separates from the contact-brushes 11 the main circuit will be broken and the illumination of the sign arrested until the segment-bar again makes contact with the brushes 11.

The pins 2 can be arranged in the letter-bars II so as to close the circuit to the proper lamps for indicating any desired letter, and the bar can be marked so as to show what letter can be indicated by it, and as these bars are movable they can be placed around the cylinder and connected with the heads G in the desired order.

I have represented in the drawings six bars K and thirty-six letter-bars II, and it is to be understood that the letter-bars are arranged so that when six of them come into action by closing the proper contacts one of the letter-bars will act with the first monogram, the next with the second, and so on around the circle, and hence the six monograms can be illuminated with the desired letter, and when the next set of letter-bars is brought around to contact with the springs on the bars K the monogram-letters can be illuminated to spell a different word, and so on. Six words can be spelled one after another, and then the seg-

ment-bar O will separate from the brushes 11 and the illumination will cease until the segment-bar again comes into contact with the brush.

60

The number of bars K and their springs will vary according to the number of monograms in the electric sign, and the number of letter-bars will vary according to the number of words to be spelled before a pause occurs in the illumination, and while it is generally most convenient to have as many holes in the letter-bars as there are pairs of springs 6 7 the letter-bars may only be provided with pins at the proper places for the given letter 70 to be illuminated, as these bars are easily changed from one place to another upon the heads G, according to the letters to be illuminated.

65

It is generally advantageous to make use 75 of the springs 6 7 in pairs, as shown; but when the heads G and the letter-bars II and pins 2 are made of conducting material it is not necessary to have the springs 6, because the pins 2, coming in direct contact with the springs 7, 80 would close the electric circuits to the respective lamps.

70

I claim as my invention—

1. The combination with the monogram of electric lamps and the circuit connections to 85 and from the same, of bars and spring-contacts carried by the bars, a shaft, heads, letter-bars and contacts upon the letter-bars and means for revolving the same and closing the circuits to the electric lamps by the pins acting upon the pairs of contact-springs, a segment-bar and contact-brush in the main circuit for closing the circuit through the spring-contacts and for breaking such circuit when the segment-separates from the contact-brush, 90 substantially as set forth.

95

2. In an automatic mechanism for electric signs, a shaft and heads, means for revolving such shaft and heads, removable letter-bars and contact-pins carried by such heads and 100 a circular range of bars and contact-springs carried by the same and circuit connections, a segment-bar upon one of the heads and a contact-brush and circuit connections, substantially as set forth.

105

Signed by me this 13th day of January, 1897.

MORTIMER NORDEN.
